CLAIM

The ornamental design for a rotating massage unit, as shown and described.

DESCRIPTION

FIG. 1 is a front, top and left side perspective view of a rotating massage unit, showing my new design;

FIG. 2 is a front elevational view thereof, the rear elevational view being identical thereto, with the handles being partially cut-away for ease of illustration;

FIG. 3 is a left side elevational view thereof, the right side elevational view being identical thereto;

FIG. 4 is a top plan view thereof, with one handle being partially cut-away for ease of illustration; and,

FIG. 5 is a bottom plan view thereof.

FIG. 1

FIG. 3

FIG. 2

FIG. 4

FIG. 5
